UNITED STATES PATENT OFFICE

153,358

DESIGN FOR A COFFEEPOT

Stanley Edwin Iredale, Hounslow, England

Application May 17, 1947, Serial No. 139,121

Term of patent 14 years

(Cl. D44—25)

To all whom it may concern:

Be it known that I, Stanley Edwin Iredale, a subject of the King of Great Britain and Northern Ireland, residing at Hounslow, Middlesex, England, have invented a new, original, and ornamental Design for a Coffeepot, of which the following is a specification, reference being had to the accompanying drawings, forming part thereof.

I claim:

The ornamental design for a coffeepot, as shown.

STANLEY EDWIN IREDALE.
